CLAIM

The ornamental design for a combined tool box vehicle bumper, bicycle carrier and air dam, as shown.

DESCRIPTION

FIG. 1 is a left front perspective view of a combined tool box vehicle bumper, bicycle carrier and air dam, showing my new design;

FIG. 2 is a front elevational view;

FIG. 3 is an elevational view of one end, the opposite end view being a mirror image thereof;

FIG. 4 is a top plan view;

FIG. 5 is a bottom plan view;

FIG. 6 is a rear elevational view; and,

FIG. 7 is a sectional view to an enlarged scale, the plane of the section being indicated by the line 7—7 in FIG. 4.

FIG. I.

FIG. 2.

FIG. 3.
